UNITED STATES PATENT OFFICE.

CHARLES HEATH AND WILLIAM ROBEY, OF BEXHILL-ON-SEA, ENGLAND.

PORTABLE HAIR-DRYING AND WARMING APPARATUS.

No. 798,677.

Specification of Letters Patent.

Patented Sept. 5, 1905.

Application filed October 29, 1904. Serial No. 230,585.

To all whom it may concern:

Be it known that we, CHARLES HEATH, a resident of 15 Sackville road, and WILLIAM ROBEY, a resident of 5 Wilton Court, Bexhill-on-Sea, county of Sussex, England, subjects of the King of Great Britain and Ireland, have invented certain new and useful Improvements in Portable Hair-Drying and Warming Apparatus, applicable also for other purposes and uses, of which the following is a specification.

This apparatus relates to improvements in apparatus especially designed for drying ladies' hair after washing or shampooing, but also applicable for use as a warmer for offices, rooms, beds, feet, and cooked foods, and has for its object the construction of an electrical heating apparatus of a portable character so arranged that the singeing of the hair and the breaking of the glass of the electric heating-lamp by contact with the damp or wet hair is obviated.

Our improved apparatus may be constructed of any suitable metal; but as the said apparatus is exposed to the damp, brass, aluminium, or zinc is preferable, the main point of the invention being the construction of a light portable cage or holder to carry a heater (an electric lamp) adapted to be held in one hand while the hair over or in contact with said cage is manipulated with the other hand.

In order that our said invention may be readily understood, reference is to be had to the following description and accompanying sheet of drawings, in which—

Figure 1 is a longitudinal elevation illustrating our improved apparatus. Fig. 2 is a sectional view illustrating the open end plate of the apparatus. Fig. 3 is a view of the cap adapted to fit over said open end, and Fig. 4 is a sectional view thereof. Fig. 5 is a sectional view of the apparatus when used as a foot-warmer.

Like letters of reference indicate corresponding parts in the several figures.

In carrying our said invention into effect we form our apparatus of end plates *a* and *b*, Fig. 1, and connect the same together by means of wires or rods *c*, which may be straight or corrugated, and to stiffen the cage thus formed we affix to and in the interior thereof and at suitable distances apart rings *d*. In the end plate *a* we provide an opening *e*, through which we pass the heater proper, the same

being a lamp (not shown in the drawings) known in the trade as a "heating-lamp" and used for electrical radiators, and to prevent the same being dragged out when in use we cover the opening *e* in the plate *a*, Fig. 2, by means of a cover-plate *f*, Fig. 3, the same being provided with hooks, catches, or the like *g*, adapted to engage in the slots *h* in the end plate *a*. The cover-plate *f* we further provide with a slot *i*, through which passes the flexible cord conveying the current to the heater. To hold the lamp securely, but without exerting great pressure on the glass, we arrange within the cage light check or coil springs *j*, Figs. 1 and 5, forming an oval ring or band, through which the heater passes and rests therein. The free end of the flexible cord we provide with any suitable connection, plug, or bayonet adapter, so as to couple up heater with any suitable source or installation of electricity. The bottom of the cage we flatten at *k*, Fig. 2, and to such flattened portion we attach a plate *l*, provided with bolts *m* to engage with the ends of the handle *n*, (the ends being detachable—*i.e.*, for the purpose of packing,) retained in position by means of the nuts *o* or equivalent fastenings. The handle we make of china, metal, or other suitable material and insulate the handle from the shank thereof to prevent said handle becoming heated.

When utilizing the heater as a foot-warmer, bed-warmer, or for warming rooms or cooked food on dishes, we dispense with the handle *n* and in place thereof use feet or carriers *p*, Fig. 5, the same being retained in position by bolts and nuts, as in the previous example.

What we claim, and desire to secure by Letters Patent of the United States, is—

1. An apparatus of the class described comprising a foraminous cage consisting of oppositely-arranged end plates, and a cylindrical series of longitudinal rods arranged in spaced relation and connecting said end plates, one of the end plates having an opening adapted to receive a heating device, a temporary closure for said opening, and holding means arranged within the cage for receiving and holding the heating device.

2. An apparatus of the class described comprising a foraminous cage consisting of oppositely-arranged end plates and a plurality of spaced rods connecting said plates, one of the end plates having an opening to admit the

passage therethrough of a heating device, a cover for said opening having interlocked connection with the end plate in which the opening is formed, and means for holding the 5 heating device within the cage.

3. An apparatus of the class described, comprising a foraminous cage having supporting means and consisting of oppositely arranged end plates and a cylindrical series of longitudinal rods arranged in spaced relation and connecting said end heads, one of the end 10

heads having a heater-receiving opening, and spring-loops arranged inside of the cage for receiving and holding the heater.

In testimony whereof we have affixed our 15 signatures in presence of two witnesses.

CHARLES HEATH.
WILLIAM ROBEY.

Witnesses:

BENJAMIN THOMAS KING,
PERCY WOODWARD.
